UNITED STATES PATENT OFFICE.

JOHN A. LAMONT, OF CHICAGO, ILLINOIS, ASSIGNOR TO AMERICAN STEEL FOUNDRIES, OF CHICAGO, ILLINOIS, A CORPORATION OF NEW JERSEY.

RAILWAY-CAR TRUCK.

1,377,704.

Specification of Letters Patent. Patented May 10, 1921.

Application filed December 27, 1920. Serial No. 433,412.

To all whom it may concern:

Be it known that I, JOHN A. LAMONT, a citizen of the United States, residing at Chicago, in the county of Cook and State of Illinois, have invented certain new and useful Improvements in Railway-Car Trucks, of which the following is a specification.

This invention relates to railway car trucks.

10 One object of the invention is to provide a simple, durable and efficient railway car truck of the six-wheel live equalizing type having a minimum wheel base to facilitate the rounding of curves.

15 Another object is to provide such a car truck as mentioned wherein simple and improved means for the equalizing of loads are provided.

20 Another object is to provide a railway car truck having its various parts arranged in a manner to coöperate to meet all of the requirements of service conditions.

25 These and other objects are accomplished by means of the arrangements disclosed on the accompanying sheets of drawings, in which—

Figure 1 is a side elevation of a railway car truck embodying my invention;

Fig. 2 is a detail sectional view taken in 30 the plane of line 2—2 of Fig. 1;

Fig. 3 is a detail sectional view taken in the plane of line 3—3 of Fig. 1;

35 Fig. 4 is a fragmentary longitudinal sectional view taken through the side frame and associated parts; and,

Fig. 5 is a top plan view of the same arrangement, parts being in section, when taken along the line 5—5 of Fig. 4, for the sake of clearness.

40 The various novel features of my invention will be apparent from the following description and drawings and will be particularly pointed out in the appended claims.

45 Referring to the figures of the drawings, it will be noted that the side frame 10 is in a single piece and is provided with three journal box openings, the end journal box openings 11 and the center journal box opening 12. Midway between these journal box 50 openings the side frame is provided with two bolster openings 13 for the reception of the end portions or legs 14 of the bolster. The end journal boxes 14' are substantially the same as those disclosed in my copending 55 application, Serial No. 422,463, filed Novem-

ber 8, 1920. Suffice it to say that springs 15 are interposed between laterally extending brackets 16 on the journal boxes and socket portions 17 formed on the side frames, said journal boxes having side flanges 18 embracing opposite sides of the side frame for maintaining their relative lateral positions within certain predetermined limits. The center journal box 19 has two laterally arranged pockets 20 on opposite sides of the center 60 journal 21, the outer end walls 22 of the journal box rising to a height to completely enclose the springs 23 located within the box 19. A spring cap 24 bridges the springs 23 on opposite sides of the journal 21 and is arranged 65 to move vertically within the end walls 22 of the spring box. The spring cap is provided with bosses 25 which extend downwardly within the springs 23 for retaining the springs in place within certain predetermined limits. At each end of the spring cap and intermediate the projections 25 is an opening 26 for a purpose to be referred to hereinafter. The intermediate portion of the spring cap is provided with a curved seat 70 75 75 for rockably receiving a pivotal projection 28 on an equalizing beam 29. The outer ends of the equalizing beam are bifurcated for the reception of eye portions 30 of hanger rods 31, the upper ends of said hanger rods 85 being pivotally connected to the ends of said equalizing beam by any suitable pins 32 located in the bifurcated portions of said beam. These hanger rods extend vertically downwardly through the associated springs 90 95 23 and through openings 33 in the lower ends of spring pockets 20. Each of the lower ends of the hanger rods 31 is provided with an eye portion 34 through which a key or pin 35 extends. Each hanger rod 31 extends through a vertical opening 36 in the associated end of an equalizing lever 37, the same end of each of which is provided with a socket portion 38 in vertical alinement with its opening 36 and rests upon and receives 100 the associated key 25 of the associated hanger rod whereby one end of each of the equalizing levers 37 is supported by a hanger rod which in each instance is suspended from the equalizing beam 29 rockably supported upon 105 the spring cap 24, which rests upon the springs 23 mounted in the central journal box 19. The opposite ends of each of the equalizing levers 37 is provided with a groove or seat 38 which pivotally rests upon 110

a pin 39 extending between side walls 40 of the side frame 10, as best shown in Fig. 3. For the most part each equalizing lever is horizontal throughout its length with the exception of the outer ends, which curve upwardly and terminate in the seat portions 38, which rest upon the pins 39. The bolster legs 14, which have the lower curved bearing portions 41, are rockably received by upwardly curved bearing portions 42 of the equalizing levers 37, the radius of curvature of the latter being greater than the radius of the curvature of the bearing portion 41 to permit proper relative rocking movement. The bearing portion of each bolster leg 14 is provided with a recess 43 for receiving a vertically extending projection 44 on the associated equalizing lever for definitely positioning the bolster legs 14 on the equalizing levers 37, whereby the bolster legs are centralized in the bolster pockets to permit free vertical movement and in a manner whereby two-thirds of the load transmitted through each bolster leg will be transmitted outwardly toward the end journal. As a result of this equalizing arrangement the spring cap and equalizing beam serve to equalize the load between the center springs and also equalizes the load between the ends of the bolsters. By using this equalizing beam 29 an even distribution to the four ends of the bolster of the load on the center plate is insured. Without the use of the equalizing beam it would be possible for the bolster center plate load to be concentrated on two, or possibly three, of the four legs. This equalizing beam instantaneously adjusts any difference in load on the four legs, which is caused by unevenness of the track, etc. As mentioned above, the fulcrum pins 39 are located relative to the bolsters 14 to give a two to one leverage, which establishes the equalizing of the load between the journal bearings. The vertical position of the fulcrum pins 39 is practically in the same horizontal plane with the engaging surface of the bolster and equalizing levers, so that the up and down movement of the equalizing levers 37 produces as nearly as possible a vertical movement of the bolster. Also, in connection with the question of equalizing and movement of the equalizing parts, attention is called to the fact that the lower ends of the hanger rods 31 in effect are lower ends of pendulums, the lower ends, however, being stationary, while the upper ends swing in rounding a curve. In this way no lateral movement is given to the equalizing levers 37 or the bolster. A liberal allowance is made for relative lateral or lengthwise movement of the center journal box with respect to the side frame for facilitating rounding a curve.

By means of this arrangement, I am able 65 to increase the available space for the end

depth of the bolster and reduce the width of the bolster ends to the least possible dimension consistent with transverse strength, thus effecting a reduction in wheel base and increasing the available space for brakes, the 70 reduction in wheel base making possible a material reduction in weight. In other words, by resting the cross bolster members 14 directly on the equalizing levers, I am able to arrange these cross bolster members midway between the end and middle pair of wheels and reduce the wheel base to the least possible dimension consistent with proper space requirements for brakes and end width of bolster members to secure proper trans- 80 verse strength. Furthermore, if springs were arranged directly between the bolster members and equalizing levers, greater width of the bolster members would be necessary to accommodate such springs and consequently 85 the length of the equalizing levers would have to be increased and the wheel base correspondingly increased.

There may be various modifications of the invention and it is my intention to cover all 90 such modifications which do not involve a departure from the spirit and scope of the following claims.

I claim:

1. In a railway car truck of the six-wheel 95 type, the combination of a side frame having spaced bolster openings, an intermediate journal box, equalizing levers pivotally supported on said side frames and operatively connected to said journal box for transmitting a load thereto, and bolster members in said openings mounted directly on said levers for transmitting loads therethrough for reducing the width of the bolster, increasing the space for brakes, and reducing 100 105 the wheel base.

2. In a railway car truck of the six-wheel type, the combination of a side frame, an intermediate journal box, equalizing levers pivotally supported on said side frame and operatively connected to said journal box for transmitting a load thereto, and bolster members mounted directly on said equalizing levers for transmitting loads therethrough for reducing the width of the bolster, increasing the space for brakes, and reducing 110 115 the wheel base.

3. In a railway car truck of the six-wheel type, the combination of a side frame, an end journal box, resilient means interposed 120 between said side frame and end journal box, an intermediate journal box, an equalizing lever supported at its outer end and having its other end operatively connected to said journal box for transmitting a load thereto, and a bolster member mounted directly on said equalizing lever for transmitting a load therethrough for reducing the width of the bolster, increasing the space for brakes, and reducing the wheel base. 125 130

4. In a railway car truck, the combination of a side frame having a bolster opening, a journal box, an equalizing lever pivotally supported on said side frame and operatively connected to said journal box for transmitting a load thereto, and a bolster member mounted directly on said equalizing lever and engaging same in a plane such that the movement of the bolster within the bolster opening is substantially vertical.

5. In a railway car truck, the combination of a side frame having a bolster opening, a journal box, a rigid equalizing lever supported at one end and operatively connected to said journal box at its other end for transmitting a load thereto, and a bolster member positioned on said equalizing lever whereby a load is transmitted therethrough and whereby the bolster member may move vertically in the bolster opening.

6. In a railway car truck of the six-wheel type, the combination of a side frame having bolster openings and an opening for an intermediate journal box, a journal box mounted in said opening, an equalizing beam for transmitting a load to said intermediate journal box, equalizing levers, each pivoted at one end to said side frame and having the other end thereof operatively connected to said equalizing beam, and bolster portions movably mounted in said bolster openings and mounted on said equalizing levers for transmitting a load therethrough.

7. In a railway car truck of the six-wheel type, the combination of a side frame having bolster openings and an opening for an intermediate journal box, a journal box mounted in said opening, an equalizing beam for transmitting a load to said intermediate journal box, equalizing levers, each pivoted at one end to said side frame and having the other end thereof operatively connected to said equalizing beam, bolster portions movably mounted in said bolster openings and mounted on said equalizing levers for transmitting a load therethrough, and means for positioning said bolster portions on said equalizing levers.

8. In a railway car truck of the six-wheel type, the combination of an intermediate journal box, resilient means carried by said journal box, an equalizing beam supported

by said resilient means for transmitting loads to said journal box, equalizing levers, one end of each of which is supported directly from the side frame and the other end of each of which is operatively connected to the equalizing beam, and bolster portions carried directly by said equalizing levers for transmitting the load therethrough.

9. In a railway car truck of the six-wheel type, an intermediate journal box, an equalizing lever, one end of which is supported and the other end of which is operatively connected to said journal box for transmitting a load thereto, and a bolster member mounted on said equalizing lever for transmitting a load therethrough, said equalizing lever and bolster member having coöperating curved portions for permitting a rocking movement of one with respect to the other.

10. In a railway car truck of the six-wheel type, an intermediate journal box, an equalizing lever, one end of which is supported and the other end of which is operatively connected to said journal box for transmitting a load thereto, and a bolster member mounted on said equalizing lever for transmitting a load therethrough, said equalizing lever and bolster member having coöperating curved portions for permitting a rocking movement of one with respect to the other, said equalizing lever and bolster member also having coöperating portions for positioning one with respect to the other.

11. In a railway truck of the six-wheel type, the combination of an intermediate journal box, springs supported by said journal box on opposite sides of the associated journal, a spring cap bridging said springs, an equalizing beam mounted on said cap, hanger rods pivotally connected to said equalizing beam on opposite sides of its center, and equalizing levers each pivotally supported at one end and each connected at its opposite end to said hanger rods whereby the loads transmitted through said levers may be equalized.

Signed at Chicago, Illinois, this 15th day of December, 1920.

JOHN A. LAMONT.
